UNITED STATES PATENT OFFICE.

ECTOR F. MARCEAU, OF EAST HARTFORD, CONNECTICUT.

INK AGITATOR.

Application filed March 19, 1927. Serial No. 176,652.

This invention relates to those devices which are adapted to be applied to the inking fountains of printing and lithographic presses for keeping the pigments of the ink 5 properly mixed with the binding mediums and insuring a uniform distribution of the required amount of ink to the desired areas of the fountain roller as long as any ink remains in the fountain.

10 A device of this character is illustrated and described in Patent No. 1,562,462 issued to me November 24, 1925, and the object of the present invention is to simplify the construction of the prior device whereby the 15 costs of producing and assembling the parts and the maintenance and care of the structure in use, are materially lowered without reduction of efficiency.

In the accompanying drawings Fig. 1 is 20 a front elevation of the device with the agitating blade carriage shown as propelled by a chain drive. Fig. 2 is a horizontal section with the releasing latch that travels with the carriage in one position. Fig. 3 shows 25 the carriage with the latch in its other position. Fig. 4 shows the carriage as propelled by a belt.

The device illustrated has a pair of clamp 30 plates 1 that are adapted to be attached to the ink fountain with which it is to be used. Fastened to the front of the clamp plates are angular brackets 2 between which a pair of parallel guide rods 3 extend. Free to rotate on a stud 4 on the front of one of the brackets 35 is a sprocket wheel 5. Turning in the other bracket is an arbor 6 on the front end of which is a sprocket wheel 7 and on the rear end of which is a bevel gear 8. Meshing with this gear is a bevel gear 9 attached 40 to a shaft 10 designed to be rotated by any convenient means. A chain 11 passes around and connects the sprocket wheels, and when the shaft 10 is rotated the chain is caused to travel in the direction indicated by the 45 arrows 11 on Fig. 1.

Mounted on the guide rods that are supported by the brackets is a carriage 12, the upper and lower edges of which are grooved to fit and slide along the rods. On the front 50 face of this carriage and rotatable on the stud 13 is a segmental sprocket wheel 14, the teeth of which are adapted when the wheel is turned up to engage the under side of the upper length of the chain and when 55 the wheel is turned down to engage with the upper side of the lower length of the

chain. Guide studs 15 are attached to the front of the carriage so as to keep the chain in position to engage the teeth of the segmental sprocket wheel. Projecting rearward from the segmental sprocket wheel is a stud 16.

Pivottally mounted in the carriage back of the segmental sprocket wheel is a latch 17 which has two forwardly extending lugs 18, 60 19 adapted, depending upon the position of the latch, to extend into the path of revolution of the stud that projects rearward from the segmental sprocket wheel. Adjustably mounted on the guiding rods are reversing 65 posts 20. These posts are clamped in the locations to which they are adjusted by thumb screws 21. These posts have inclined slots 22 in the plane of the latch, and the ends of the latch are beveled so as to easily 70 engage with the walls of these slots. The carriage has an arm 23 with an adjustable clamp 24 and thumb nut 25 for fastening the ink agitating blade 26 in position.

When the teeth of the segmental sprocket 80 wheel are engaged with the upper length of the chain, as shown in Fig. 1, this wheel is turned until its rearward projecting stud 16 engages the under side of the lug 18 on the latch. This locks the wheel and the chain 85 then draws the carriage toward the right. After the carriage has traveled the length of the ink fountain the beveled end of the latch strikes the beveled wall of the slot in the reversing post at the right and the latch 90 is turned so that the lug 18 is disengaged from the stud 16. The segmental sprocket 95 wheel is then free and it rotates until its teeth engage the lower length of the chain and the rearwardly projecting stud 16 engages the lug 19 on the latch, which has been thrown forward by the engagement of the latch with the reversing post. With the parts engaged in this manner the segmental sprocket wheel is locked so that the chain 100 will cause the carriage to travel toward the left. This movement to the left continues until the end of the latch engages the reversing post on the left side and the latch is reversed freeing the stud 19 from the lug 16 so that the segmental sprocket wheel teeth 105 are again turned into engagement with the upper length of the chain and the carriage again propelled toward the right.

This mechanism, having but the single 110 segmental sprocket wheel with its stud adapted to be engaged by the lugs projecting

from the reversing latch, the position of which is changed at each end of the movement of the carriage by engagement with the reversing posts, propels the carriage with the ink agitating blade back and forth regularly as long as the driving mechanism keeps the chain in motion.

Instead of having a segmental sprocket wheel and chain, as above described, the carriage may be provided with a segment of a pulley 27 that may be engaged by a belt 28, the friction between the belt and the pulley surface being sufficient under some circumstances to propel the carriage back and forth. In this case the latch is reversed and the pulley turned from engagement with the upper to the lower length of the belt and back again in the same manner as with the sprocket and chain.

The invention claimed is:—

1. An ink agitator comprising supporting brackets designed to be fastened to an ink fountain, a guide way extending between said brackets, a carriage fitted to travel back and forth on said way, said carriage having means for the attachment of an agitating blade, endless traveling means mounted on the brackets, a segmental wheel rotatably mounted on the carriage and adapted to be intermittently engaged by the upper and lower lengths of said endless traveling means, a latch movably mounted on the carriage, and means at the ends of said guide way adapted to reverse said latch, which latch when in one position engages and locks the segmental wheel in contact with one length of the endless traveling means and when in its other position engages and locks said wheel in contact with the other length of the chain.

2. An ink agitator comprising supporting brackets designed to be fastened to an ink fountain, a guide way extending between said brackets, a carriage fitted to travel back and forth on said way, said carriage having means for the attachment of an agitating blade, an endless traveling chain mounted on the brackets, a segmental sprocket wheel rotatably mounted on the carriage and adapted to be intermittently engaged by the upper and lower lengths of said chain, a latch movably mounted on the carriage, and means at the ends of said guide way adapted to reverse said latch, which latch when in one position engages and locks said sprocket wheel in contact with one length of the chain and when in its other position engages and locks the sprocket wheel in contact with the other length of the chain.

3. An ink agitator comprising supporting brackets designed to be fastened to an ink fountain, a guide way extending between said brackets, a carriage fitted to travel

back and forth on said way, said carriage having means for the attachment of an agitating blade, an endless chain mounted on the brackets, a segmental sprocket wheel rotatably mounted on the carriage and adapted to be intermittently engaged by the upper and lower lengths of said chain, a stud extending rearwardly from said segmental sprocket wheel, a latch provided with lugs and movably mounted on the carriage, and means at the end of said guide way adapted to reverse said latch and move first one lug into the path of said stud then the other lug into the path of said stud and thus intermittently lock the sprocket wheel with opposite lengths of said chain.

4. An ink agitator comprising supporting brackets designed to be fastened to an ink fountain, guide rods extending between said brackets, a carriage fitted to travel back and forth on said rods, said carriage having means for the attachment of an agitating blade, wheels mounted on the brackets, means for rotating one of said wheels, an endless conveyor passing around said wheels, a segmental wheel rotatably mounted on the carriage and adapted to intermittently engage opposite lengths of said conveyor, a stud extending rearwardly from said segmental wheel, a latch movably mounted on the carriage, and posts adjustable on said guide rods and adapted to engage and reverse said latch, which latch when in one position is engaged by said stud and locks the segmental wheel in one position against rotation, and when in its other position is engaged by said stud and locks the segmental wheel against rotation in another position.

5. An ink agitator comprising supporting brackets designed to be fastened to an ink fountain, guide rods extending between said brackets, a carriage fitted to travel back and forth on said rods, said carriage having means for the attachment of an agitating blade, sprocket wheels mounted on the brackets, means for rotating one of said sprocket wheels, an endless chain passing around said sprocket wheels, a segmental sprocket wheel rotatably mounted on the carriage and adapted to be intermittently engaged by the opposite lengths of said chain, a stud extending rearwardly from said segmental sprocket wheel, a latch movably mounted on the carriage and posts adjustable on said guide rods and adapted to engage and reverse said latch, which latch when in one position engages and locks the sprocket wheel in contact with one length of the chain and when in its other position engages and locks the sprocket wheel in contact with the other length of the chain.

ECTOR F. MARCEAU,
